ATTORNEY.

UNITED STATES PATENT OFFICE.

WILLIAM J. KENELY, OF ELIZABETH, NEW JERSEY.

STOVEPIPE-HOOD.

1,047,951.

Specification of Letters Patent. Patented Dec. 24, 1912.

Application filed March 13, 1912. Serial No. 683,512.

To all whom it may concern:

Be it known that I, WILLIAM J. KENELY, a citizen of the United States, residing at Elizabeth, in the county of Union and State 5 of New Jersey, have invented certain Improvements in Stovepipe-Hoods, of which the following is a specification.

The objects of the invention are to provide an improved hood for gathering the 10 rising vapors, odors and the like and deflecting the same from a cook stove into the stovepipe; to provide suitable means of escape for such vapors, which shall not interfere with the draft or efficient operation of 15 the stove; to provide means for closing the vent, which means shall be readily operated, to secure a rigid but detachable hood; to secure simplicity of construction and installation, and to obtain other advantages and 20 results as may be brought out in the following description.

Referring to the accompanying drawings, in which like numerals of reference indicate the same parts throughout the several 25 views, Figure 1 is a side elevation of my device applied to a length of stove pipe, parts of the hood being broken away for the better disclosure of the invention; Fig. 2 is a plan view of the same; Fig. 3 is a vertical 30 section on line A—A of Fig. 2; Fig. 4 is a front elevation with the hood removed, and Fig. 5 is a cross-sectional view on line B—B of Fig. 4, looking in the direction indicated by the arrows.

35 In the specific embodiment of the invention illustrated in said drawings, 1 designates a length of stovepipe to which the invention is applied. As the principal application of the invention is to any stovepipe 40 leading from the ordinary kitchen range to the chimney proper, it is evident that the invention is not restricted to a pipe of circular cross section, such as shown in the drawings, but is applicable to the various 45 sizes and shapes of pipe in use.

50 Circumferentially of the pipe, and extending approximately half way around the same, is a strap of sheet-metal 2, held thereto by rivets 3 near each end, or other equivalent means. The major portion of the strap 2 is offset, as at 4, to provide a slot 5 between the strap and the pipe. The pipe is apertured as at 6, said aperture commencing between the upper and lower edges of the

strap 2, preferably, and extending downward for some distance below said strap.

The sheet-metal at each of the vertical edges of this aperture is doubled back as at 7, see Fig. 5, and then returned forward again substantially parallel to itself in 60 spaced relation thereto, as at 71, forming thereby a slideway 8 between the portions 7 and 71 mentioned. The slideways 8 thus extend slightly under the strap 2, and are prevented from undue expansion or inadvertent distortion by engagement with the 65 said strap.

Slidably mounted within the above mentioned slideways 8, is a slide or vent regulator 9, preferably constructed of sheet metal 70 similar to that of which the pipe is composed, and curved transversely of itself concentric therewith. A stop 10 is stamped from, and bent outwardly perpendicular to the slide 9, preferably central of the lower 75 edge, so that when the slide is raised or opened, the stop 10 engages the strap 2, thereby limiting the upward movement of the slide. The material of which the slide is composed is bent outwardly, above the 80 strap 2, and then bent upwardly again at 12 with reduced width of metal to form a handle, the upper extremity of such handle 12 being provided with an outwardly projecting finger-piece 13 suitable for the manual control and operation of the slide. The 85 outwardly bent portion 11 forms a shoulder or stop to limit the downward movement of the slide 9, and at the same time it positions the handle 12 away from the pipe 1 90 so as to be readily operable. In the absence of the hood next to be described, this shoulder engages the upper edge of the strap 2 whereby further displacement downwardly 95 is prevented.

The hood, of which cursory mention is above made, comprises essentially a fan-shaped metallic top 14, the diverging edges 15 of which are approximately in radial planes of the stove pipe 1, when operatively 100 assembled. The outer edge 16 is preferably arcuate, making the top 14 thereby a segment of a circle. The inner or vertex end of such top is cut away upon a circular line 17 to register with the inner edge of the strap 105 2. Preferably at the intersection of such arcuate line 17 and the radial side edges 15, are secured as by rivets 18, angular pieces

or hooks 19 which bend downwardly and are adapted to take into the slot 5 to removably support the hood and retain the same against lateral displacement.

5 Preferably integral with the top 14 of the hood are its depending and preferably plane sides 20, 20, of triangular shape with one vertex registering with the point of intersection of the outer arcuate edge 16 and the 10 respective radial edge 15 of the top. The inner edges 21 of such triangularly shaped sides 20 are substantially vertical, as shown best in Fig. 1, and adapted to meet and engage the cylindrical surface of the pipe 1 15 along longitudinal elements thereof.

A segmental collar 22 inwardly connects the lower, inner vertices of the sides 20, being attached thereto by rivets 23 or the like. This collar is curved to engage the convex 20 surface of the pipe when in operative position, and the moment of inertia introduced by the weight of the hood tends to rotate the same about the angular pieces or hooks 19 as an axis, such moment being balanced 25 into stable and static equilibrium by the reaction of the strip 22 bearing against the pipe, thereby holding the hood in position. The triangular shape and arrangement of the sides inclines the top 14 downwardly as 30 it projects outwardly by virtue of which rising vapors will be deflected inwardly upon being intercepted by the hood.

When the hood is in operative position, the shoulder 11 of the slide 9 engages the 35 inner edge of the hood top as shown in Fig. 3.

The removal of the hood is effected by first sufficiently raising the slide to disengage the hood; then lifting the hood, the 40 hooks 19 disengage the strap 2, and the hood can be removed entirely from the pipe.

The operation of the device is evident and self explanatory. The hot gases, odors, and so forth which rise from the stove are intercepted by the hood and deflected inwardly as already stated. With the slide 9 open, the gases pass on into and up the stovepipe. The presence and probably the inclination of the hood prevents the down draft of cold 50 air into the stovepipe which would interfere with the draft of the stove. The slide is provided for use when it is desired to regulate or close the vent into the pipe, and more especially when it is desired to remove the 55 hood entirely. It may here be stated that the action of the gases as above stated produces an inward current which will draw into the stove pipe other gases than those which would normally rise and be intercepted by the hood.

In order to insure sufficient frictional engagement of the slide 9 with the slideways 8, I double back the edges 24 of the slide designed to slide therein, as shown in Fig. 5.

65 The expansive tendency of such structure

retains the slide in frictional engagement with the slideways, as desired, and if in the course of time the expansive tendency may decrease, the doubled-over portion may be spread again with any suitable tool.

Having thus described the invention, what I claim is:

1. The combination with a pipe having a lateral aperture, of a strap mounted on the outside of said pipe adjacent to said aperture having a portion at right angles to the length of the pipe and spaced therefrom, a slide for said aperture working between said strap and pipe, and a hood having hooks adapted to detachably take into the slot between said strap and pipe on opposite sides of said slide.

2. The combination with a pipe having a lateral aperture, of a strap mounted upon the outside of said pipe with a portion extending at right angles to the length of the pipe and spaced therefrom, a hood having a top and depending sides, hooks at the upper edges of the sides of said hood adapted to take into the slot between said strap and the pipe, and a strip connecting the lower edges of said sides of the hood and adapted to engage the pipe.

3. The combination with a pipe having a lateral aperture, of a strap mounted upon the outside of said pipe with a portion extending at right angles to the length thereof and spaced therefrom, a slide for said aperture adapted to move up and down between said strap and pipe, a hood having a top and depending sides, hooks at the upper edges of the sides of said hood adapted to hook over said strap on opposite sides of said slide, and a strip connecting the lower edges of the sides of the hood and adapted to lie against the pipe.

4. The combination with a pipe having a lateral aperture, of a strap mounted upon the outside of said pipe adjacent to said aperture having a portion at right angles to the length of the pipe and spaced therefrom to form a slot between said strap and pipe, a hood having hooks adapted to detachably take into the slot between said strap and pipe near the ends thereof, a slide for said aperture in the pipe working between said strap and the pipe and having stops one above and the other below said strap, and a handle for said slide projecting above said strap and hood.

5. The combination of a pipe having a lateral aperture with integral wings at the longitudinal edges of said aperture bent outwardly apart and returned toward each other to form slideways, a strap upon the outside of said pipe having a portion extending transversely of the pipe adjacent to said aperture and spaced from the pipe, a slide having doubled edges working in said slideways and lying between said strap and

the pipe, a hood having hooks adapted to detachably engage said strap, stops for said slide above and below said strap, and a handle above said hood for operating the 5 slide.

6. The combination of a pipe having a lateral aperture with slideways at its edges extending longitudinally of the pipe, a hood with a top spaced at its adjacent edge from 10 said pipe at the upper part of said slideway and having side walls depending on opposite sides of said aperture and slideways, co-operating means on said hood and pipe for detachably mounting the hood upon the pipe, 15 and a slide for the said aperture in the pipe adapted to move up and down in said slideways through the space between the pipe and top edge of the hood.

7. The combination of a pipe having a lateral aperture with slideways at its edges 20 extending longitudinally of the pipe, a hood with a top spaced at its adjacent edge from said pipe at the upper part of said slideway and depending sides fitting close to the said pipe outside said slideways, co-operating 25 means on said hood and pipe for detachably mounting the hood upon the pipe, and a slide for the said aperture in the pipe adapted to move up and down in said slideways with a handle portion projecting above the 30 hood through the space between the top of the same and the pipe.
